UNITED STATES PATENT OFFICE.

FRANK W. POOLE AND EDMUND RAY MANWELL, OF MARYSVILLE, CALIFORNIA.

DESIGN FOR A BADGE, EMBLEM, OR SIMILAR ARTICLE OF JEWELRY.

48,948.

Specification for Design.

Patented Apr. 25, 1916.

Application filed February 28, 1916. Serial No. 81,067. Term of patent 3½ years.

To all whom it may concern:

Be it known that we, FRANK W. POOLE and EDMUND RAY MANWELL, citizens of the United States, residing at Marysville, in the county of Yuba and State of California, have invented a new, original, and ornamental Design for a Badge, Emblem, or Similar Article of Jewelry, of which the following is a specification, reference being had to the accompanying drawing, forming part thereof.

The figure is a perspective view of a badge, emblem, or similar article of jewelry embodying our design.

We claim:

The ornamental design for a badge, emblem, or similar article of jewelry, as shown.

FRANK W. POOLE.

EDMUND RAY MANWELL.

Witnesses:

W. J. GOODMAN,
DONNELL GREELY.
